UNITED STATES PATENT OFFICE

92,841

DESIGN FOR A COMBINATION LAMP AND CLOCK CASING

George Wagner Gable, Philadelphia, Pa.

Application March 29, 1934, Serial No. 51,242

Term of patent 3½ years

To all whom it may concern:

Be it known that I, GEORGE WAGNER GABLE, a citizen of the United States, residing at 4146 Parkside Avenue, in the city and county of Philadelphia, State of Pennsylvania, have invented a new, original, and ornamental Design for a Combination Lamp and Clock Casing, of which the following is a specification, reference being had to the accompanying drawing, forming part thereof:

Figure 1 is a front view of a combination lamp and clock casing, showing my new design.

Figure 2 is a side view of the same.

I claim:

The ornamental design for a combination lamp and clock casing, as shown.

GEORGE WAGNER GABLE.
